[57] **CLAIM**

The ornamental design for a foldable lap desk, as shown
and described.

DESCRIPTION

FIG. 1 is a front, top and left side perspective view of a
foldable lap desk showing my new design;
FIG. 2 is a back, bottom and right side perspective view
thereof; and,
FIG. 3 is a left side elevational view thereof, and a
mirror image of the right side.

FIG. 1
